UNITED STATES PATENT OFFICE.

HENRY E. REEVE, DECEASED, LATE OF NEW YORK, N. Y.; BY HELEN REEVE, EXECUTRIX, OF BROOKLYN, NEW YORK.

SPRING MOTOR FOR SIGNALING MECHANISM.

Application filed August 28, 1924. Serial No. 734,572.

My invention relates particularly to what plates 10 and 11 is secured a gear 17 to which is secured a spring pressed pivoted pawl 18. The active face of this pawl normally engages the tooth of the single toothed ratchet 19 which is rotatably mounted on the shaft 16 and secured to the pinion 20. 60

Among the objects of the present invention are to provide a simple, inexpensive but reliable form of release mechanism, to simplify the wind-up ratchet mechanism 10 and insure proper operation without interference, to construct and arrange the parts so that the main spring can be readily wound and assembled with the remainder of the mechanism and to facilitate accurate 15 and permanent assembly of the parts of the frame of the motor. The preferred form of mechanism for carrying out these objects separately and collectively is shown in the accompanying two sheets of drawings. 20

Fig. 1 is a front view of a pull box spring motor embodying the improvements of my invention.

Fig. 2 is a plan view of the same.

Fig. 3 is a front view of the mechanism 25 with the front plate and operating handle omitted.

Fig. 4 is a rear view.

Fig. 5 is a detail sectional view showing 30 the method of mounting the main spring.

Fig. 6 shows mechanism for initially winding the main spring.

Fig. 7 is a detail sectional view showing the method of holding one of the gear shafts in place.

Fig. 8 is a perspective detail showing the 35 means for spacing the frame plates.

The frame of the motor has a front plate 10 and a back plate 11. These plates are spaced apart by channel-like or angular 40 posts 12 and held in their proper relation by the screws 13. Each post member 12 has two lugs 14 on each end seated in recesses or holes in the frame plates. This is a very simple and inexpensive construction and 45 yet it is very easy to assemble and the parts are held rigidly against twisting or displacement when the screws 13 are tightened. Each of the screws 13 is preferably located within the channel of one of the post members. 50

The signal mechanism has a wheel 15 mounted on a shaft 16 and constructed and operated as more fully set forth in my application #640,241.

55 On the signal shaft and between the

main driving spring 21 has its inner end hooked on to the pin 22 which projects from the sleeve 23. This sleeve 23 is mounted on the shaft 24 outside of the frame and is normally locked to the shaft by the pin 25. The outer end of the spring 21 is secured to a bolt member 26. A bracket 27 is provided for holding the spring in place. 70 This bracket is held to the frame plate 11 by means of the screw 28 and the bolt 26 and in its turn holds the pin 25 from accidental disengagement. This construction makes it possible to assemble the spring and 75 other parts in a very simple manner. For instance, the spring is hooked to the pin 22 and the bolt 26 before being wound up. At this time the pin 25 has not been inserted. The winding shaft 29 however is inserted in the outer end of the sleeve 23 and temporarily connected by a pin 30. Then the spring is wound without disturbing the rest of the mechanism. When the desired degree of winding has been completed the pin 25 is inserted through the sleeve and the 80 shaft 24 and the bracket 27 placed and secured in position. Thereupon the winding handle 29 is released and the pin 30 withdrawn. 85

The gear 31 meshes with the pinion 20 for transmitting the power of the driving spring to the signal wheel. The wig-wag 32 is carried by a pivot 33 and driven by a toothed wheel 34 which is mounted with the pinion 35 on the sleeve 36 on shaft 36'. This shaft is held in place by the bearings in the plates 10 and 11 and by the cover plates 37 and 38. Each of these plates 37 and 38 is held in position, for instance by a rivet 39 which serves as a pivot for it and a screw 40. To remove the shaft 33 or the shaft 36' it is simply necessary to remove the screw 40, swing the plate 37 so as to clear the end of the shaft and then draw out the shaft. Secured to the gear 31 is a pinion 41 which meshes with the segmental gear 42. This latter has a sleeve 43 and is mounted between the plates 10 and 11 on the shaft 44 which 100 extends through to the rear and has upon it 105 110

a spring 45 tending to hold the shaft 44 and the arm 46 in the position shown in Figs. 1 and 2 where the arm 46 abuts against the stop 47 which is carried by a part 48 of the front plate 10. This part 48 serves as an abutment for the segmental gear 42. The arm 46 has a pawl 49 which is pivoted at 50 and spring pressed toward the axis of the shaft 44. This pawl extends around one edge of the arm 43 into the path of movement of the pawl 51 which is pivotally secured at 52 on the segmental gear 42. This pawl 51 is spring pressed toward the axis of the shaft 44. The operating or pull lever 53 is secured on the outer angular end of the shaft 44 in any suitable manner.

Normally the two pawls 49 and 51 are in engagement with each other so that when the lever 53 is pulled down the arm 46 rotating with it rotates also the segmental gear 42 because of the interengagement of the pawls 49 and 51. This rotates the pinion 41 and the gear 31 clockwise as viewed from the front and thus rotates the pinion 20 and single toothed ratchet 19 anticlockwise. Should the handle 53 be released before the ratchet 19 makes a complete revolution the spring 21 will return the rotating parts to their normal positions without having operated the signal shaft 16 and the signal wheel 15. In case the lever is pulled far enough to give one or more complete rotations to the single toothed ratchet 19 and thus allow the pawl 18 to again catch the ratchet 19, then, in that case, as soon as the handle 53 is released the main spring 21 will rotate the gear 31, pinion 20, ratchet 19, pawl 18 and gear 17 and the signal shaft 16 and wheel 15 one or more turns depending upon the number of times the single toothed ratchet 19 has been rotated by the winding action of the lever or handle 53. This single toothed ratchet connection between the pinion 20 and the gear 17 makes it impossible to produce anything but a full signal rotation of the signal wheel and thus makes it impossible to send a partial signal as is the case when the ratchet connection between the pinion and gear on the signal shaft has more than one tooth.

Although the pawls 49 and 51 are normally interlocked or interengaged, it will be noted that when the lever handle 53 is pulled far enough to obtain the requisite rotation of the single toothed ratchet 19 and the handle is then released the spring 45 will return the handle to its initial position more rapidly than the main driving spring returns the segmental gear 42. This means that the pawls 49 and 51 will become separated and the outer tip of the pawl 51 will immediately move toward the axis of the shaft 44 and out of the path of movement of the operating tip of the pawl 49 being stopped by abutment 54. Should the oper-

ating lever handle 53 be again pulled before the signal has been completed the pawl 49 cannot again engage the pawl 51 and it is therefore impossible to interfere with the signal which has once been started. As the signal is being completed however the segmental gear 42 carries the pawl 51 around with it until the tip of the pawl engages the stationary abutment 48 on the plate 10 and thus forces the tip of the pawl 51 outward into the path of movement of the pawl 49 ready for operation when the lever handle 53 is again pulled. The operating face of the pawl 49 could be fixed to the arm 46 if it were not for the fact that it must be able to clear the pawl 51 should the operating lever be held down while the signal is being sent and not released until after the pawl 51 had traveled back to its normal position of rest as shown in Fig. 3.

I claim:

1. In a spring motor, a combination of a frame having mounting plates, a main driving shaft pivotally supported therein, a sleeve mounted on said shaft outside of said frame, movable means of connection between said sleeve and said shaft, a spring on the outside of said frame connected to said sleeve and to said frame, said sleeve having a socket to receive means for rotating said sleeve.

2. In a spring motor, a frame containing a gear train, a main driving shaft extending beyond said frame, a sleeve on said shaft extending beyond said frame, a spring outside of said frame and connected to said sleeve and to said frame, a pin connecting said sleeve and said shaft and a bracket on the outside of said frame for holding said spring in place.

3. A spring motor comprising a frame, a main shaft, a driving spring therefor, a winding shaft, a spring for returning said winding shaft independently of said main spring, a gear rotatable on said winding shaft independently thereof and meshing with a gear on said spring shaft, an arm carried by said winding shaft and pivoted spring pressed interengaging pawls carried by said arm and by said segmental gear.

4. A spring motor comprising a frame, a main driving shaft extending through to the rear of said frame, a driving spring mounted on the outer end thereof, a winding shaft extending through said frame, a return spring mounted on the rear end thereof outside of said frame, a pull lever mounted on the front end of said winding shaft, a segmental gear mounted on said winding shaft, a gear on said driving shaft meshing with said segmental gear and pawl connections between said winding shaft and said segmental gear.

5. In a signal mechanism, a lever actuated gear, a main spring and winding shaft hav-

- ing driving connection with said gear, a shaft, a pinion free to turn on said shaft, a single toothed ratchet secured to said pinion, a gear carried by said shaft, a pawl carried by said gear and positioned to latch with said ratchet and an escapement connected to said gear.
6. Signal mechanism comprising a gear, a shaft therefor, a pinion mounted to turn independently on said shaft, a driving spring for turning said pinion, means for winding said spring, a ratchet secured to said pinion and having but a single tooth, a spring actuated pawl carried by said gear and co-acting with said ratchet and an escapement driven by said gear.
7. In a pull box, a driving spring, a shaft therefor, a pull lever, a shaft therefor, a gear mounted to turn independently on said lever shaft, a releasable pawl between said lever shaft and said gear, a gear on said spring shaft meshing with said first mentioned gear, a second gear on said spring shaft, a wheel, a shaft therefor, a pinion mounted to turn on said wheel shaft and meshing with said second gear, a single toothed ratchet attached to said pinion, a gear carried by said wheel shaft, a pawl carried by said latter gear for coacting with said ratchet, and escapement mechanism driven by said latter gear.
8. Signal mechanism comprising a shaft, a pawl pivotally carried by said shaft, a gear independently oscillable on said shaft, pawl pivoted to said gear and adapted to engage said first mentioned pawl, a wheel, and a gear train between said wheel and said gear including a ratchet.
9. In a signal mechanism, a rotatable gear, a spring actuated pawl pivotally carried thereby and a stop for said gear adapted to actuate said pawl.
10. In a signal mechanism, an operating lever, a shaft therefor, an arm carried by said shaft, a pawl movably carried by said arm, an oscillating member, a pawl movably carried thereby and coacting with said first mentioned pawl, abutments for said member, said arm and said latter pawl, and means for automatically moving said latter pawl from a position permitting coaction with said first mentioned pawl when the two become separated.
11. In a signal mechanism, an oscillatory
- lever, a shaft to which said lever is fastened, an arm carried by and fastened to said shaft, a pawl mounted on said arm, a second oscillating member, a pawl mounted thereon, stops for said oscillating members, and an abutment for said latter pawl whereby this pawl is swung into a position permitting coaction with said first mentioned pawl, and means for automatically moving said latter pawl from a position permitting coaction with said first mentioned pawl when the latter pawl becomes free to move from its coacting position.
12. In a signal mechanism, two oscillable members, pawls carried thereby and normally interlocked when the parts are at rest, each of said pawls being movable away from the other pawl.
13. In a signal mechanism, two oscillable members, spring actuated and pivoted pawls carried by said members and normally interlocked when said members are at rest.
14. In a signal mechanism, two oscillable members, pawls yieldably carried thereby, and means for normally holding said pawls in engagement when said members are at rest.
15. In a construction of the character described, frame plates having perforations or recesses, angular spacing columns having abutting shoulders for said plates and lugs extending into said perforations and screws passing through one plate and into the other between the sides of said column for holding the parts together.
16. In a construction of the character described, frame plates having perforations or recesses, spacing columns of angular cross section having a part of the ends formed to serve as abutting shoulders for said plates and a part of said ends formed to pass into or through said perforations, and means for holding the plates against said abutting shoulders.
17. In a construction of the character described, frame plates having perforations or recesses, sheet metal spacing columns bent to form an angular cross section and having the ends formed as described, and recesses at the ends of the angular bend to allow for the expressed fins.

HELEN REEVE,
Executrix of Henry E. Reeve, deceased.
